UNITED STATES PATENT OFFICE.

JOHN A. PEER, OF BROOKLYN, NEW YORK, ASSIGNOR OF ONE-HALF TO
THOMPSON & NORRIS, OF SAME PLACE.

ROLLER-SKATE.

SPECIFICATION forming part of Letters Patent No. 339,317, dated April 6, 1886.

Application filed April 20, 1885. Serial No. 162,730. (No model.)

To all whom it may concern:

Be it known that I, JOHN A. PEER, of Brooklyn, in Kings county and the State of New York, have invented a certain new and useful Improvement in Roller-Skates, of which the following is a specification.

I will describe a skate embodying my improvement and then point out the various features of the improvement in claims.

In the accompanying drawings, Figure 1 is a side view of a skate embodying my improvement, the rollers being shown in dotted lines. Fig. 2 is an inverted plan thereof, one pair of rollers being shown as swung around. Fig. 3 is an inverted view of the forward part of the skate with the forward pair of rollers, their journals, and bearing-piece removed. Fig. 4 is a top view of the bearing-piece. Fig. 5 is a transverse section taken at the plane of the dotted line *x x*, Fig. 2. Fig. 6 is a vertical section taken at the plane of the dotted line *y y*, Fig. 2. Fig. 7 is a front view of certain parts as seen when looking at them in the direction indicated by the line *z*.

Similar letters of reference designate corresponding parts in all the figures.

A designates the foot-piece of the skate. It may be made of wood or any appropriate metal and shaped to suit the taste.

B B' designate two brackets or projections, made of metal, preferably malleable cast-iron. Their under sides incline toward each other, the under side of the forward bracket, *B*, inclining rearwardly toward the foot-piece, and the rear bracket, *B'*, inclining forwardly toward the foot-piece. The brackets may be secured to the foot-piece by screws *a* or otherwise. The forward bracket has formed with it slide-ways *b*, in which and below the foot-piece fit the shanks of clamping-jaws *C*, that are operated by a screw, *D*, having right and left hand threads engaging with tapped holes in lugs at the inner ends of the shanks of the clamping-jaws. The heel-clamps may be of any desirable kind, and can be connected with the foot-piece and operated in any approved manner.

Each of the brackets *B B'* has on the under side a spheroidal protuberance, *c*, and a flange, *d*, extending about half-way around it and made flaring inside and spheroidal on the ex-

terior. The surface *e*, from which the protuberance *c* and flange *d* extend, inclines or bends laterally from the center toward the foot-piece in both directions.

Each pair of rollers is connected to a bearing-piece, *E*. The bearing-piece of each pair of rollers has an upper surface, *f*, which from the center inclines downwardly in both directions laterally. It has a cavity, *g*, which fits around the flange *d* of the corresponding bracket, and a circular flange, *h*, which fits between the flange *d* and the adjacent protuberance *c*. A center-pin, *P*, or screw passes loosely through a hole at the center of each bearing-piece and engages with a tapped hole in the protuberance *c* of the corresponding bracket. Between the shank or body of the screw and a cavity, *i*, with which the under side of the bearing-piece is provided, and above the head of the screw, a block of india-rubber or analogous material, *H*, fits tightly. By forcing the screw farther into the protuberance of the bracket with which it engages the block *H* may be expanded so circumferentially that it will fit more tightly between the screw and the cavity *i*, and by withdrawing the screw partly from said protuberance the block will be allowed to contract circumferentially, so that it will fit less tightly between the screw and the cavity *i*. Preferably a metal washer, *I*, is arranged around the body or shank of each screw and between its head and the adjacent block *H*. When the user of the skate inclines the foot-piece laterally, the brackets *B B'* are caused to rock laterally upon the bearing-pieces *E*. Owing to the inclination of the brackets this causes the bearing-pieces to slide toward each other on the side at which the foot-piece is depressed, and consequently away from each other at the side of the foot-piece which is elevated. The pairs of rollers thus range themselves with their axes in the position of radii of a curve and facilitate the travel of the skate around a curve.

In the adjustment of the bearing-pieces as described, the surfaces *e* of the brackets *B B'* rock on the surfaces *f* of the bearing-pieces *E*, protuberances *c* of the brackets rock and turn in the flanges *h* of the bearing-pieces, and the flanges *d* rock and turn in the cavities *g* of

the bearing-pieces. These adjustments of the bearing-pieces are resisted by the blocks H, which always also tend to bring the foot-piece to a horizontal position above the bearing-pieces. The movements of the skater will act to bring the foot-piece to the horizontal position.

Above the flanges *d* of the brackets B B', and nearer to the center of the skate, there are arranged on the under surfaces of the brackets B B' blocks of india-rubber or like material J. They are fitted into semi-cylindrical flanges *j*, extending from the brackets and secured in place by screws K, whose bodies or shanks pass through them and engage with tapped holes in the brackets. Washers of metal L are made to surround the bodies or shanks of these screws between the heads and the blocks J.

20 The bearing-pieces E have in the edges cavities that fit the blocks J. The blocks J resist the swinging of the bearing-pieces and tend to bring the latter back to their normal position after they have been swung around. By 25 adjusting the screws K these blocks J may be expanded circumferentially or allowed to contract, and the resistance which they offer to the swinging of the bearing-pieces can thus be varied to adapt the skates to persons of different weight.

It will be observed that the ends of the flanges *d* act as stops to prevent a too extended lateral movement of the bearing-pieces E.

Although I have only shown one of the bearing-pieces swung around in Fig. 2, I do not mean to intimate that one would thus swing around while the other would remain in its normal position. I have only done this for convenience of illustrating the bearing-pieces in different positions in a single view.

The journals M for the rollers N may be cast integral with their bearing-piece, as shown, in conjunction with the forward bearing-piece, B, or they may be formed in one shaft fitted 45 in lugs *k*, extending from their bearing-piece, as illustrated, in connection with the rear bearing-piece, B'.

My skate is simple, cheap, and durable, and, withal, it is capable of traveling around very short curves.

50

What I claim as my invention, and desire to secure by Letters Patent, is—

1. In a skate, the combination of rollers connected to a bearing-piece, E, the inclined bracket or projection B, the inclined surfaces *e f*, and the center-pin or screw P, passing loosely through the bearing-piece E and engaging with the bracket or projection B, substantially as specified.

2. In a skate, the combination of rollers connected to a bearing-piece, E, the inclined bracket or projection B, the inclined surfaces *e f*, the block H, and the center-pin or screw P, passing loosely through the bearing-piece E and engaging with the bracket or projection B, substantially as specified.

3. In a skate, the combination of rollers connected to a bearing-piece, E, the inclined bracket or projection B, the inclined surfaces *e f*, the spheroidal protuberance *c*, the flange *h*, the cavity *i*, the center-pin or screw P, passing loosely through the bearing-piece E and engaging with the bracket B and the block H, substantially as specified.

4. In a skate, the combination of rollers connected to a bearing-piece, E, the inclined bracket B, the inclined surfaces *e f*, the spheroidal protuberance *c*, the flange *h*, the flange *d*, the cavity *g*, and the center-pin P, the ends of the flange *d* constituting stops to limit the lateral movement of the bearing-piece E, substantially as specified.

5. In a skate, the combination of rollers connected to a bearing-piece, E, the inclined bracket or projection B, the inclined surfaces *e f*, the spheroidal protuberance *c*, the flange *h*, the flange *d*, the cavity *g*, the center-pin or screw P, the pin or screw K, and the block J, for resisting the lateral movement of the bearing-piece E, substantially as specified.

JOHN A. PEER.
